UNITED STATES PATENT OFFICE.

OTTO H. MOHR, OF KENTFIELD, CALIFORNIA, ASSIGNOR TO MOHRLITE COMPANY, OF SAN FRANCISCO, CALIFORNIA, A CORPORATION OF CALIFORNIA.

DESIGN FOR A STREET-LIGHTING FIXTURE.

46,955.

Specification for Design.

Patented Feb. 16, 1915.

Application filed August 27, 1913. Serial No. 787,039. Term of patent 7 years.

To all whom it may concern:

Be it known that I, OTTO H. MOHR, a citizen of the United States, residing at Kentfield, Marin county, State of California, have invented a new, original, and ornamental Design for Street-Lighting Fixtures, of which the following is specification, reference being had to the accompanying drawings, forming part thereof.

Figure 1 is an elevation of the street lighting fixture, a suitable standard therefor be-

ing shown in dotted lines. Fig. 2 is a vertical cross section of the street lighting fixture.

I claim—

The ornamental design for a street lighting fixture, substantially as shown.

OTTO H. MOHR.
